UNITED STATES PATENT OFFICE.

HENRY A. WISE WOOD, OF NEW YORK, N. Y., ASSIGNOR, BY MESNE
ASSIGNMENTS, TO DETROIT TRUST CO., TRUSTEE, OF DETROIT,
MICHIGAN, A CORPORATION OF MICHIGAN.

PRINTING-MACHINE.

No. 831,257.

Specification of Letters Patent.

Patented Sept. 18, 1906.

Application filed October 1, 1900. Renewed December 4, 1905. Serial No. 290,173.

To all whom it may concern:

Be it known that I, HENRY A. WISE WOOD, a citizen of the United States, residing at New York, in the county of New York and State of New York, have invented a new and useful Printing-Machine, of which the following is a specification.

The aim of this invention is to improve the traveling-cylinder web-printing press; and to this end the invention consists of the devices described and claimed in this specification and illustrated in the accompanying five sheets of drawings, in which—

Figure 1 is a plan view of a printing-press with my improvements applied thereto. Fig. 2 is a sectional elevation of the press shown in Fig. 1. Fig. 2^a is a view showing a modification. Figs. 3 and 4 are diagrammatic views similar to Fig. 2, showing the operating parts in different positions. Fig. 5 is a similar sectional view illustrating a web-perfected form of traveling-cylinder printing-press with my improvements applied thereto. Fig. 6 is a view similar to Fig. 3, illustrating a modification; and Fig. 7 is a diagram illustrating the action of the web when certain of my devices, as hereinafter described, are not used.

The especial aims of my invention are, first, to provide devices whereby the web will be handled more easily in a traveling-cylinder or traveling-cylinder perfecting-web press, and, second, to provide improved inking devices.

In web-printing presses as now organized and used the rapid reciprocation of the cylinder or cylinders causes an air-pressure in front of and a suction behind the moving cylinder. This action is illustrated in Fig. 7, in which an impression-cylinder is shown moving to the right over a stationary bed. In this case the web to the right of the cylinder will be bellied in between the guide 17 and the cylinder and will be bellied out between the guides 17 and 18, as shown. The web to the left of the cylinder will be sucked away from the cylinder between the guide 16 and the cylinder and will be sucked down between the guides 15 and 16, as shown. This strain on the web, due to the air-pressure and suction caused by the rapid movement of the cylinder, is very objectionable in practice. The reasons for this are that when the press

is run at a high rate of speed the web is apt to be broken from this cause, especially if a weak place or splice occurs in the web, and that the tendency of the same is to effect and disarrange the register between the two impressions in a web-perfected press. To remedy these evils, I have provided parts which I term "wind-shields or guards," which I place in such relative positions with respect to the exposed portions of the web as to tend to prevent the web being bellied out or pulled in by air pressure or suction. 65

The second part of my invention consists in a peculiar inking device embodying moving ink-distributing tables.

Referring now to the first three sheets of drawings, I have shown therein a single-cylinder web-printing press embodying my improvements.

Referring to the drawings and in detail, A A' represent the side frames of the machine, between which is mounted or arranged in any of the usual manners the stationary bed B, upon which the form or forms can be secured.

G G represent two reciprocating carriers, which constitute a traveling carriage. Mounted in this carriage is an impression-cylinder C, which is adapted to coact with the form or forms on the bed B, so as to make an impression on either or both its forward or backward movements. One or more form-rollers F F are mounted in the reciprocating carriage at each side of the impression-cylinder C, and a distributer F' is preferably arranged to coact with each pair of form-rollers. A single-form roller of course could be used at each side of the impression-cylinder. At each end of the stationary bed is mounted an inking device. Each inking device consists, preferably, of four ink-tables L, L', L², and L³, the ink-tables L' and L³ being arranged stationary in the side frames and the two inking-tables L and L² being arranged and having mechanism whereby they will be laterally reciprocated to nicely distribute the ink. Arranged beyond each of these sets of inking-tables is a fountain H, which may be of any of the usual constructions and which may have the usual spreading or carrying roll h. The carriers G, constituting the reciprocation-carriage, are extended and carry therein on each side one or more distributer-rollers F² 100 105

$F^2 F^2 F^2$, as shown in the drawings. As the carriage is reciprocated these distributor or carrier rollers take the ink from the fountain H and spread the same on the inking-tables, 5 where the ink is nicely distributed by the peculiar action before described, and from the ink-tables the ink is taken by the form-rollers F F and spread nicely and evenly upon the form or forms. By this mechanism I 10 have provided a very simple and efficient inking mechanism whereby very delicate and perfect printing can be done by reason of the large and accurate distribution.

The path of the web and the mechanism 15 for driving the various parts may be arranged as follows: The impression-cylinder may carry gears which may mesh with stationary racks mounted on the bed in the usual manner, so that as the cylinder is reciprocated 20 the same will roll to register with the form or forms. The web may be led from a roll W, which may be mounted in any of the usual ways. The web w from the roll is first led in between the continuously-running feeding-in 25 rollers 10, 11, and 12 or any of the continuously-acting feeding-in devices which may be driven by any of the usual gearing. From the feeding-in rollers the web is passed around a looping-in roller 13, which may be 30 mounted in suitable arms 14 in guides in the side frames. From the feeding-in looper the web passes around a stationary guide or roll 15 to a guide or roll 16, mounted in the carriers G at the left of the impression-cylinder 35 C. From the guide or roll 16 the web passes under the impression-cylinder C and then up over a guide or roll 17, also mounted in the carriers G. From the guide or roll 17 the web is led to a stationary guide or roll 18 up 40 over a looping feeding-out roller 19, which may be mounted in suitable arms 23, and then is fed continuously out of the press by means of continuously-running feeding-out rollers 20, 21, and 22 or any of the usual continuously-running feeding-out devices which 45 may be positively driven by any suitable mechanism not necessary here to describe at length. The arrangement of this feeding mechanism is well understood and is so proportioned and designed that the web will be 50 held stationary while the cylinder is in impression and so that the web will be shifted or fed forward while the cylinder is out of impression at either end of the bed, the web being fed continuously into and out of the 55 press.

The arms 23 and 14, that connect to the loopers, may be connected to common arms 24, which may be mounted on a shaft 240 in 60 the main frames A and A'. These arms 24 have studs 25 secured therein, which studs carry rollers 26, which bear on cams 27. Springs 410 are connected to one end of the arms 24 and stationary parts and serve to 65 keep the rollers 26 on the cams 27.

28 designates a shaft which, if desired, may be the driving-shaft of the machine and which has suitable tight and loose pulleys P' and P mounted thereon. Power from the driving-shaft 28 is taken by means of pinions 70 29, mounted thereon, and gears 290, mounted on the cam-shaft 35.

30 designates a shaft which is connected to actuate the impression-cylinder. This shaft is driven from the cam-shaft 35 by means of 75 bevel-gears 34 and 33 and parallel shaft 320 through the bevel pinion and gear 32 and 31, as indicated. If desired, the shaft 30 may be the shaft to which power is primarily applied, and the driving-shaft 28 may be arranged so that its pinion will mesh with the gears 290, which are then placed on the shaft 30, as indicated in dotted lines. This last construction is used where it is desired to reciprocate a very heavy carriage. On the 80 outside ends of the shaft 30 are mounted cranks 36, which connect by links or pitmen 37 to pivoted levers or arms 38, which are mounted on a shaft 40, secured in the main frames. These vibrating arms 38 connect by 85 links 39 to the impression-cylinder C or to the carriers G, whereby the impression-cylinder will be reciprocated over the form-bed. On the other end of the shaft 320 is mounted a miter-gear 41, which meshes with a miter-gear 42, and turning with the miter-gear 42 is a gear 43, which meshes with a gear 44, secured on a shaft 45. Mounted on this shaft 45 is a box-cam 46, having a groove 47.

48 designates a pivoted arm or lever which 90 has a roll 49 engaging the groove 47 of the cam 46, and by this means the arm 48 will be vibrated back and forth.

The tables L and L², as before described, are mounted in the side frames, so as to be 95 capable of lateral movement. The arm 48 connects by a link 50 and by an adjustable connection 51 to a long rod or link 52, which is used to vibrate the movable inking-tables and which may be also used to operate the 100 ink-fountains. This arm connects at each end to a lever 53, which has the usual pawl-and-ratchet connection to the ink-supplying rolls H of the ink-fountains. The vibrating tables L have short racks 54, and the vibrating tables L² have short racks 55, with which mesh toothed segments 56 and 57, which are mounted on studs depending from the stationary tables L'. These sectors are given a short vibration by means of a short link and 105 connection 58 and 59 to the link 52. By this mechanism as the link 52 reciprocates the inking-rollers of the fountain are turned and the movable ink-tables are reciprocated laterally, so that the ink will be nicely distributed and spread, as before described.

To prevent the rapid reciprocation of the impression-cylinders from bagging or stretching the web, I provide wind-shields, which are arranged very close to the web. The 110

particular wind-shields shown in the drawings are constructed as follows: A number of rods, as the four rods 60, are carried across the press between the side frames and carry 5 a thin shield or guard 61, which is arranged between the guides 15 and 18, as shown, and which may be arranged to bear directly upon or may be arranged at a very slight distance above the web. Between the roll or guide 10 16, carried by the carriage, and the bottom of the impression-cylinder I arrange a metallic guard or shield 62, and between the roll or guide 17 and the bottom of the impression-cylinder I arrange a similar guard or shield 15 63. As the cylinder is reciprocated these guards or shields will prevent the web from ballooning or being stretched from the air pressure or suction and are intended to add greatly to the rapid operation of the press. 20 The impression-cylinder C has a gap or depression c^3 , in which may be mounted a set of grippers c^2 and a reel c' , by which a tympan or blanket c can be tightly stretched around the periphery of the impression-cylinder. A 25 portion of the impression-cylinder is also cut away, as at c^4 , on each side of the depression c^3 . If preferred, the gap or depression may be made larger than shown, thus dispensing with the cut-away portions, which are 30 formed at each side of the depression. This cut-away portion of the impression-cylinder c^4 and the depression c^3 are so arranged relatively to the impression peripheral surface of the impression-cylinder that when the impression-cylinder is moved so that the same 35 is off the form in either direction, as indicated in Figs. 3 and 4, the web will not touch the impression surface or cylinder, being held therefrom by the lower ends of the 40 wind guards or shields 64 and 63. By this means when the shifting of the web around the impression-cylinder takes place the web will be shifted without rubbing or bearing on the impression-surface and will also be raised 45 away from the surface of the ink-tables L^3 , whereby the web is fed about the impression-cylinder while the same is over one of the ink-tables and so held that it will not be blurred or smeared by contact either with 50 the impression-cylinder or the ink-table.

In Fig. 5 I have shown a sectional elevation embodying a perfecting form of a printing-press arranged to have the improvements before described. In this press an additional bed B' and impression-cylinder C' are used. The loopers 13 and 19 are mounted in common arms 130, which may be actuated by cams in any of the usual manners. The inking apparatus is arranged, as before 55 described, for each bed B and B' , and the wind guards or shields are arranged about the web, as described. From the first impression-cylinder the web passes around the stationary guide or roll 70, beneath the adjustable register-roll 71, up over the sta-

tionary guide or roll 72, then to the guide or roll 75, carried by the carriage, under the second impression-cylinder C' , then around the guide or roll 76, also carried by the carriage G , to the feeding-out device. This path 70 of the web will enable the same to be perfected. If desired, with this mechanism I can arrange a wind guard or shield at the right of the press between the guides or rolls 70 and 72, and the same may consist of a 75 thin metallic shield or guard 74, carried by the cross-rods 73 73. The operation of the parts in the perfecting form of the press is substantially the same as that in the single-cylinder press, and it is thought that a specific description of the same is not necessary. 80

In Fig. 6 I have shown a modification of the wind-shield that is used above the impression-cylinder. The guard instead of consisting of a thin metallic shield or frame 85 is made in the form of an endless belt 103, which may be made out of stiff or heavy canvas and which is turned around the rolls 100 and 101, mounted in the frames, as shown, and which has its ends connected to the carriage, as by rods 104. With this modification as the cylinder reciprocates the endless belt will run back and forth and will form a shield, which will prevent the web from bellying or ballooning out by the air pressure 90 or suction.

In some cases instead of arranging the wind-shield above the web to prevent the same from ballooning I may arrange the shield between the web and the cause of the 100 pressure—that is to say, in the arrangement shown I may arrange the shield below the web, and such an arrangement is clearly within the scope of my invention. This arrangement is shown in Fig. 2^a, the wind-shields 610 620 being made of sheet metal and secured in the carriage. The free ends of the same pass over rollers 611, so that said shields will reciprocate with the cylinder. 105

I am aware that many of the details that I 110 have herein described may be applied by a skilled mechanic to other forms of presses, and the particular arrangements and relative locations of the co-operating elements may be greatly varied by a skilled mechanic 115 and still accomplish the functions I have described.

Having thus fully described my invention, what I claim, and desire to secure by Letters Patent, is—

1. The combination in a web-printing press of a form-bed, a traveling impression-cylinder coacting therewith, and a wind guard or shield arranged relatively to the web so as to prevent air displacement, due to the 125 movement of the cylinder, from affecting the web.

2. The combination in a web-printing press of two form-beds, a traveling impression-cylinder coacting with each form-bed, 130

and wind guards or shields arranged relatively to the web so as to prevent air displacement, due to the movement of the cylinders, from displacing the web.

- 5 3. The combination in a web - printing press of a traveling impression-cylinder, guiding mechanism whereby the web may be led to, under, and from the impression-cylinder, and a wind guard or shield arranged over 50 the impression-cylinder so as to prevent displacement of the air, due to the movement of the impression-cylinder, from affecting the web.
- 15 4. The combination in a web - printing press of two form-beds, a traveling impression-cylinder coacting with each form-bed, guiding mechanism for leading the web through the machine, substantially as described, and wind guards or shields arranged 55 over the impression-cylinders.

- 25 5. The combination in a web - printing press of a traveling carriage carrying an impression-cylinder, a guide arranged in the carriage at one side of the impression-cylinder, and a wind guard or shield arranged in the carriage to prevent displacement of the web between the said guide and cylinder.

- 30 6. The combination in a web - printing press of a traveling carriage carrying an impression-cylinder, a guide arranged at each side of the impression-cylinder adapted to direct the web to, under, and from the impression-cylinder, and wind guards or shields arranged in close proximity to the guides.

- 35 7. The combination in a web - printing press of two form-beds, a traveling carriage carrying an impression-cylinder coacting with each form-bed, guides carried by the carriage adapted to direct the web under 40 each impression-cylinder in turn, and wind shields or guards mounted in close proximity to the guides carried by the carriage, and arranged to prevent the displacement of the air caused by the movement of the cylinders 45 from deranging the web.

8. The combination in a web - printing press of a traveling impression - cylinder, guiding mechanism for directing the web down under, and up from the impression-

cylinder, and wind shields or guards arranged 50 over the guiding mechanism and between the same and the impression-cylinder.

9. The combination in a web - printing press of two form-beds, a traveling carriage carrying an impression - cylinder coacting 55 with each form-bed, guiding mechanism carried by the carriage adapted to direct the web under each impression-cylinder in turn, stationary wind-shields arranged in close proximity to the guiding mechanism, and wind-shields mounted in the carriage, and arranged between the guiding mechanisms and the impression-cylinder.

10. The combination in a web - printing press of a traveling carriage carrying an impression-cylinder, and a guide at each side of the impression-cylinder, with wind shields or guards arranged between the guides and the bottom of the impression-cylinder.

11. The combination in a printing-press of 70 a traveling carriage carrying two impression-cylinders, guides arranged at each side of the impression - cylinders, and wind shields or guards arranged between each guide and the bottom of the impression-cylinder.

12. The combination in a web - printing press of a traveling carriage carrying a cut-away or recessed impression-cylinder, and wind guards or shields arranged at each side of the impression-cylinder so as to prevent 80 air-pressure on the web, and also so as to hold the web clear of the impression-cylinder as the shift of the web takes place.

13. The combination in a web - printing press of a traveling carriage carrying two cut-away or recessed impression-cylinders, and wind shields or guards arranged at each side of each impression-cylinder, adapted to prevent air-pressure on the web, and to hold the web away from the impression-cylinders as 90 the shift takes place.

In testimony whereof I have hereunto set my hand in the presence of two subscribing witnesses.

HENRY A. WISE WOOD.
